G. BABCOCK.
TELEPHONE EXCHANGE SYSTEM.
APPLICATION FILED AUG. 8, 1913.

Patented June 26, 1917.

UNITED STATES PATENT OFFICE.

GARRISON BABCOCK, OF CHICAGO, ILLINOIS, ASSIGNOR TO TELECHRONOMETER COMPANY, OF ROCHESTER, NEW YORK, A CORPORATION OF NEW YORK.

TELEPHONE-EXCHANGE SYSTEM.

1,230,835.

Specification of Letters Patent. Patented June 26, 1917.

Original application filed February 17, 1910, Serial No. 544,429. Divided and this application filed August 8, 1913. Serial No. 783,661.

To all whom it may concern:

Be it known that I, GARRISON BABCOCK, a citizen of the United States, residing at Chicago, in the county of Cook and State 5 of Illinois, have invented a certain new and useful Improvement in Telephone-Exchange Systems, of which the following is a full, clear, concise, and exact description, reference being had to the accompanying 10 drawings, forming a part thereof.

My invention relates to service meters for telephone exchange systems, and has reference particularly to that class of service meters in which the metering mechanism is located at the substations. 15

It is an object of my invention to provide a meter of the class referred to of such a nature that the meter is under the joint control of the subscriber and of the 20 apparatus located at the exchange which apparatus is controlled by the called subscriber in answering the call. My invention refers particularly to such a combination of parts that the operation of registering a call initiated at any substation is accomplished by means of the operation at such substation of the mechanism ordinarily used in calling the central exchange. 25

After connection has been made by the 30 operator at the exchange with the calling line and such connection has been extended to the called line, response on the part of the called subscriber causes operation of the relay mechanism associated with the cord 35 circuit employed in making the connection in such a manner as to reverse the polarity of the current supplied to the answering end of the cord circuit and in this manner apparatus is actuated at the calling substation which apparatus by its operation 40 serves to reset the register ready for registering another call.

In carrying out my invention I prefer to employ at the substation a polarized relay 45 which is responsive to a reversal in current direction as a result of which the resetting magnet is actuated when the polarized relay is operated.

After having been properly reset to be actuated the meter may be operated either 50 by the mechanical operation of the switch hook or may be electrically operated by a circuit closed at the motion of the switch hook from its talking to its normal position. 55

This case is a division of my previous application Serial No. 544,429 filed Feb. 17, 1910.

In the drawings:

The accompanying illustration is a dia- 60 grammatic drawing showing the telephone system complete with the apparatus at one of the substations in its talking condition while the apparatus at the other substation is shown in its normal or resting condition. 65

In illustrating my invention, I have shown the substation A connected by line wires 1 and 2 with the exchange, the line circuit there terminating in the tip and sleeve springs 3 and 4 respectively of the 70 line jack J. The springs 3 and 4 normally make contact with the contact springs 5 and 6 respectively. The spring 5 is connected with the winding of the line relay 7, the other terminal of which is connected by 75 wire 8 with the negative pole of the battery B. The spring 6 is connected by wire 9 with the positive pole of battery B.

The register mechanism 22 is adapted to be operated by a lever 23 pivoted at 24 by 80 means of a pawl 25 pivoted at 26 to such lever. The lever 23 also serves as a polarized armature for the resetting magnet 31 of the registering mechanism, as a result of which when the magnet 31 is properly energized the lever 23 is moved forcibly downward thus resetting the pawl 25 in position to subsequently operate the registering mechanism. This motion of the lever 23 releases the spring 32 which is comparatively 85 stiff and permits it to engage the contact 31 carried by the contact spring 33.

At the substations there is arranged the subscribers telephone set comprising the transmitter T and the receiver R which is 95 adapted to be hung on the hook 19. The

latter is pivoted at the point 29 and cooperates with a block of insulating material 18^a resting on the spring 18, which when in its operative position engages the 5 contact 17 and when depressed, by hanging the receiver on the hook, engages the contact 18^b. The induction coil is indicated by 12 and one extremity of the primary winding thereof connected by wire 20 with 10 contact 17; the other extremity of said coil indicated by 21 to the transmitter, to one terminal of the winding of the resetting magnet 31 at 21^a to contact spring 33.

An operating magnet 85 is provided for 15 actuating the registering mechanism by rotating the lever 23 on its pivot after it has been set into the operative position by the magnet 31. The energizing of said operating magnet having been controlled by the 20 moving of the switch or hook 19.

The winding of the magnet 85 is connected between the line conductor 1 and the spring 18^b adapted to be engaged by the spring 18 when the hook switch is in its 25 normal position. Switch springs 86 and 87 are included in this path for the purpose of interrupting the circuit of the magnet 85 when the lever 23 is moved downward at its right hand end by the energization of the 30 magnet to advance the registering mechanism 22. The springs 86 and 87 which are in contact when the lever 23 is in its set position, are so conformed at their upper ends as to engage rollers 88 and 89 carried 35 by the right hand end of the lever 23. When the lever is in its set position the spring 86 engages the roller 88 but the engagement between the springs 86 and 87 serve to lift the spring 87 from engagement 40 with the roller 89. When, however, the lever 23 is moved downward at its right hand end the roller 89 comes into engagement with the spring 87 while the roller 88 is moved from engagement with the spring 86 45 thus allowing the spring 86 to spring away to the left from engagement with the spring 87 and open the circuit through the energizing winding of the magnet 85. The conformation of the upper end of the spring 87 50 serves at this time to retain the lever 23 in the position to which it has been moved by the magnet 85.

The springs 32 and 33 are also conformed at their upper ends to engage the rollers 32' 55 and 33' which are carried by the left hand end of the lever 23. The spring 33 serving, when the lever 23 is moved downward at its left hand end, to lock the lever in such position until it is positively operated by means 60 of the magnet 85.

The centers of the rollers 32' and 33' and the free ends of the springs 32 and 33 are so disposed that when the lever 23 is in its upper or actuated position no tension is exerted by said springs to throw the lever in 65

one direction or the other. However when the lever 23 is retracted to its resetting position the rollers permit the engagement of the spring 32 and the contact 31'.

The transmitter and primary winding of the induction coil 12 are included between the winding 31 and the spring 17 of the hook switch so that there is no interruption in the path of the current through said winding when the magnet 31 is short circuited by the closing of the contacts 31' and 32. Ringer 90 may be connected between the lined conductor 1 and the spring 87 with a condenser interposed to prevent the flow of steady current. 75

The resetting magnet 31 is connected between the line wire 1 and the wire 21 and the contact springs 32 and 33 are connected to the terminals of the resetting magnet as indicated so that when the lever 23 has been 80 moved downward to its resetting position the closure of the contacts 32 and 31' establishes a short circuit between the terminals of the resetting magnet, and further operation of such magnet is therefore prevented 85 until the lever 23 is again moved upward by reason of the operation of the switch hook 19. A further result accomplished by the closure of the contacts 32 and 31' is that the impedance of the resetting magnet 31 at the 90 calling substation is removed from the line circuit during talking. 95

The switch hook 19 is so disposed relatively to the contacts 17 and 18 that when in its depressed position which is its normal position under the weight of the receiver R, it engages the block of insulation 18^a carried by the spring 18, and thus separates the contacts 17 and 18 and interrupts the circuit through the primary winding of the 100 induction coil 12.

The winding of the operating magnet 85 is connected at one extremity to the spring 86 and at its opposite end it is joined by the line 85^a to the line wire 1. The coils of this 110 magnet are so wound that current in one direction will effect its energization to actuate the armature 23 to open the contacts 86 and 87. The opening of which cuts the magnet 85 out of the main line circuit until 115 resetting magnet has been again energized.

Assuming that the receiver R has been removed from the switch hook 19, as shown at the substation A, the register 22 is actuated and the contacts 17 and 18 are closed, and thus in a manner well known in the art, the line relay 7 is energized by the pulling up of its armature 34 against the contact 35, and a circuit is closed between the wires 8 and 9 through the line lamp 36 to signal the operator at the exchange that a connection is desired. The current in the line at this time flows through the transmitter T, the primary winding of the induction coil 12 and through wires 20 and 21 in a direction which 120 125 130

does not effect the energizing of the resetting magnet 31. This condition continues until the direction of the current flow in the substation line is reversed, through the extremities of the central office apparatus and the act of answering in by the called subscriber. When the called subscriber answers the current of the polarity flows through the resetting magnet 31 causing the armature 23 to be retracted setting the registering mechanism in position to be actuated. When the lever 23 reaches its lower or retracted position the contacts 32 and 31' are closed thus short-circuiting the magnet 31.

15 The reversal of current flow in the line circuit is accomplished, as follows:

The cord circuit herein shown consists of two strands 37, 38, extending from the tip and sleeve 39, 40 of the answering plug P to the tip and sleeve 41 and 42 of the calling plug P', respectively. The strands 37 and 38 have connected in them the listening key 43 and the ringing key 44, and these strands are interrupted conductively, although continuous inductively by the condensers 45, 46 in a manner well known in the art. An operator's set 47 is provided in the usual manner, such set being connected with the listening key 43.

30 The battery B has its negative terminal connected by the wires 8 and 48 with one terminal of the winding of the tip supervisory relay 49, the other terminal of which is connected by wire 50 with the answering end of the strand 37. The same terminal of the battery B is also connected by wire 51 with one terminal of the winding of the tip supervisory relay 52, the other terminal of which is connected with the calling end 40 of the strand 37 by wire 53. The positive pole of the battery B is connected by wire 54 with one terminal of the winding of the sleeve supervisory relay 55, the other terminal of which is connected by wire 56 with the calling end of the strand 38. The same pole of the battery B is also connected by wires 54 and 57 with the back contact 58 of the armature 59 of the relay 55.

The armature 59 is connected by wire 60 with one terminal of the winding of the sleeve supervisory relay 61, the other terminal of which is connected by the wire 62 with the answering end of the sleeve strand 38. A generator G is provided, and has its 55 field winding 63 connected by wires 64 and 65 directly with the terminals of the battery B. The positive and negative brushes 66 and 67 of the generator are connected respectively by wires 68 and 69 with the positive pole of the battery B and the front contact 70 of the armature 59.

60 The armatures 71 and 72 of the supervisory relays 49 and 52 are normally in engagement with their back contacts 73 and 74, which are connected with the super-

visory lamps 75 and 76 respectively, the other terminals of these lamps being connected together by the wire 9 to the positive pole of the battery B. The armatures 71 and 72 are connected together by the wire 70 75, and are also connected by the wire 78 with the spring contact 79 of the plug seat switch S, the other member 80 of which is connected by wire 81 with the negative pole of the battery B.

75 As a result of the circuit connections above described, when the operator answers a call received by the flashing of the lamp 36 and inserts the answering plug P into the jack J, the line relay 7 is deenergized by the separation of the jack springs 3 and 4 from the contacts 5 and 6 respectively, and current is now supplied from the battery B through the supervisory windings 61 and 49 to the line wires 1 and 2 in the same direction as it was previously supplied through the springs 5 and 6, as a result of which no energization of the magnet 31 occurs, since the core 13 is magnetized in the same direction.

80 This condition continues until the called subscriber, after having been properly connected by the insertion of the calling plug P' in the jack J', and operation of the signaling mechanism 90 at the called substation, responds by removing his receiver from his switch hook. When the called subscriber removes his receiver from the switch hook he closes a circuit through the substation apparatus, thus causing the energization 85 of the relay 55. This results in pulling up the armature 59 and interrupting the circuit from the positive pole of the battery B through wires 57 and 60 to the winding of the supervisory relay 61, and closing a path between the negative brush of the generator G through wire 69, contact 70, armature 59, and wire 60 to the same terminal of the relay 61. The potential developed by the generator G should be approximately 90 100 twice the potential of the battery B, and as a result current is caused to flow through the battery B in opposition to its voltage and the resultant voltage impressed upon the strands 37 and 38 is of about the same 105 value as the voltage of the battery B but in a reverse direction. The generator G is especially constructed so as to supply direct noiseless current to the substation circuit which is adapted for talking purposes, 110

115 and by its flow through the primary winding of the induction coil 12 it reverses the polarity of the magnet 31, and since the contacts 32 and 31' are open and the contacts 17 and 18 are closed, the resetting 120 magnet 31 is energized, thus setting the register 22, at the close of which operation the contacts 32 and 31' are closed to prevent subsequent accidental operation of the magnet 31.

The armature 23 being set in the actuated position as a result of the current reversing in the line following the answering of the called subscriber remains in this position until the calling subscriber hangs or replaces his receiver upon the hook 19. By this act the spring 18 is closed in the engagement with the contact 18^b and the current thereupon flows through the operating magnet 85 from line wires 1 and 2 through the contacts 86 and 87. The energizing magnet 85 causes the armature 23 to be returned to its normal position and in so doing the previously established connection is recorded on the indicator 22.

From the circuits above described it will be noticed that the supervisory lamps 75 and 76 are lighted when the apparatus at the corresponding substations is returned to its normal position by hanging the receivers upon the hooks and that flow of current through the supervisory lamps 75 and 76 is interrupted by the opening of the plug seat switch S, when the calling plug P' is returned to its normal position.

From the above it will appear that if the called subscriber does not respond, although the registering mechanism at the calling substation has been actuated, the calling subscriber is not improperly charged because when he makes the next call, it will effect no actuation of the registering mechanism, inasmuch as it was not reset during the preceding calling operation. In other words by my system, although a call may be registered, when the called party is not available, still the charged call is in effect credited since no advance of the registering mechanism is made for the next call which may be responded to by the called subscriber.

The arrangement of the meter operating mechanism at the substation D is identical with that shown and described for substation A, the only difference being that in connection with the substation D the lever 23 is shown in its lower position and the switch hook 19 is shown in its normal position supporting the receiver R.

50 I claim as my invention:

1. In a telephone exchange system, the combination of a main exchange, telephone lines extending from substations to such exchange, a meter at one of such substations, an operating magnet for the meter 85, means controlled by the hook switch for energizing such magnet, a resetting magnet 31 for the meter, and means 59 controlled by the response of the called subscriber for reversing the direction of current flow in the line to actuate such resetting magnet.

2. In a telephone exchange system, the combination of a main exchange, telephone lines extending from substations to such exchange, a meter at one of such substations,

an operating magnet for the meter, means controlled by the hook switch for energizing such magnet, a resetting magnet for the meter, means controlled by reversal of the current in the line for actuating such resetting magnet, and means for locking the meter in either its operated or set position.

3. In a telephone exchange system, the combination of a main exchange, telephone lines extending from substations to such exchange, a meter at one of such substations, an operating magnet for the meter, means controlled by the hook switch for energizing such magnet, a resetting magnet for the meter, means controlled by reversal of the current in the line for actuating such resetting magnet, means for closing a shunt between the terminals of the resetting magnet by its operation, and means for opening the actuating circuit of the operating magnet by its operation.

4. In a telephone exchange system, the combination of a main exchange, telephone lines extending from substations to such exchange, a meter at one of such substations, an operating magnet for the meter, means controlled by the hook switch for energizing such magnet, a resetting magnet for the meter, means controlled by reversal of the current in the line for actuating such resetting magnet, means for closing a shunt between the terminals of the resetting magnet by its operation, and means for opening the actuating circuit of the operating magnet by its operation.

5. In a meter adapted for use at a telephone substation, the combination of registering mechanism, means for electromagnetically operating the registering mechanism, and switch springs controlled by the operation of the actuating mechanism adapted to open the circuit of the operating mechanism by its operation, such springs adapted to retain the operating mechanism in its actuated position.

6. In a meter adapted for use at a telephone substation, the combination of registering mechanism, an operating magnet for the register, a resetting magnet, means for interrupting the operative relation of the resetting magnet at the end of operation of the meter and means automatically actuated by the talking apparatus at the substation at the close of a conversation for actuating the operating magnet, reestablishing an operative condition of the resetting magnet and opening the operating circuit of the operating magnet.

7. A meter adapted for use at a telephone substation, consisting in the combination of registering mechanism, a magnet for operating such mechanism, a magnet for resetting the registering mechanism, switch springs adapted to close a shunt circuit between the terminals of the resetting magnet

by the resetting operation, switch springs adapted to be operated by the actuation of the operating magnet to open its operating circuit, and means controlled by the return 5 of the switch hook to its normal position for energizing the operating magnet to cause actuation of the meter, interruption of the

circuit through the operating magnet, and interruption of the shunt circuit between the terminals of the resetting magnet.
